(No Model.)

E. RUANE.

WIRE FENCE.

No. 252,702.

Patented Jan. 24, 1882.

UNITED STATES PATENT OFFICE.

EDWARD RUANE, OF CENTRE RUTLAND, VERMONT.

WIRE FENCE.

SPECIFICATION forming part of Letters Patent No. 252,702, dated January 24, 1882.

Application filed July 13, 1881. (No model.)

To all whom it may concern:

Be it known that I, EDWARD RUANE, of Centre Rutland, in the county of Rutland and State of Vermont, have invented certain new 5 and useful Improvements in Wire Fences, of which the following is a specification.

My invention relates to an improved connection for the barbed plates or wires of a metallic fence, and to an improvement in the construction of posts, affording means for more securely attaching the wires or plates to the said posts.

In the accompanying drawings, Figure 1 is an elevation of a portion of my improved barbed fence. Fig. 2 is a section of the fence taken 15 on line $x-x$ of Fig. 1. Fig. 3 is an enlarged sectional view of the post and clamping mechanism, taken on line $y-y$ of Fig. 1. Fig. 4 is a cross-section of the bottom of the post and socket, taken on line $z-z$ of Fig. 2. Fig. 5 is a perspective 20 view of the spring-crest. Fig. 6 is a similar view of a modification of the crest. Fig. 7 is a view of the lower end of one of the posts; and Fig. 8 is a detail showing the end of one of the barbed plates. Fig. 9 is a front view of the clamping 25 device shown in section in Fig. 3, the washers and barbed plate being removed. Fig. 10 is a front view of one of the washers.

Similar letters of reference indicate corresponding parts.

Ordinarily wire fences are made with wooden 30 posts, the strands of wire being secured to the posts by staples driven into the posts. By my invention the fence is made entirely of metal, the posts A A being of cast-iron and the wires or plates B B preferably of steel. The posts 35 A A are preferably cast hollow, and with as many quadrangular T-slotted chambers a a and through-slots or inward depressions a' a' as there are to be strands of wire in the fence.

In cross-section the posts will be in most cases 40 round, and in outline they will be, by preference, in the form of an elongated ellipse, or tapering at both ends, the greatest diameter being at about the surface of the ground when 45 the posts are set, at which point I provide them with the flange c. In some instances that portion of my improved post which extends into the ground will be a plain cone of sufficient length to support the post firmly. In other 50 instances (to adapt the post for very loose soil) the bottom of the post will be formed with the

blades or wings d d, and in still other instances the bottom of the post will be formed with the slot e and the depression or way e' for locking the post into the post-socket F, which socket 55 is provided upon the inside with the stud or pin f'', adapted to follow the depression or way when the post is lowered into the socket and to enter the slot e, as shown in Fig. 4. When the socket is used, of course the bottom of the 60 post will be a plain cone without the wings d d, and the socket may or may not be provided with the wings f' f', as desired.

The quadrangular T-slotted chambers a are cast on the side of the post A, as shown in Fig. 1, 65 in which chambers the nuts h h of the clamping-bolts H H are adapted to be placed, for holding the plates or wires B B at the ends or at any point between the ends, the washers i i' being placed upon the bolts each side of the 70 plates or wires, as shown in Fig. 3. The washer i' is provided with the flange i'' for sheltering the plates and the washer i at the top.

Upon the back side of the washer i' is formed the stop j, which is of a size to just fit in the 75 upper portion of the T slot in the quadrangular T-slotted chamber, and serves to guide the washer and prevent the nut h from turning in the chamber when the bolts H H are turned for clamping the wires. When the bolts H H 80 are screwed tightly against the wires and washers the inner ends of them enter the slots or depressions a' a' in the posts, as shown in Fig. 3.

The wires or plates B B, which, as above mentioned, are preferably of steel, are barbed 85 upon the upper and lower edges thereof, which barbs are formed by cutting diagonally into the edges of the plates, and bending the pointed pieces of metal thus separated outwardly, so as to stand at about right angles to the main 90 part of the plates. The ends of the plates B B are divided for a suitable distance, as shown in Fig. 8, so that the parts b' b' may be bent for attachment to the posts or to the crescent-shaped springs E E. These springs are of 95 steel, and they are for the purpose of accommodating the contraction and expansion of the wires, thus relieving the posts of undue tension caused by the contraction of the wires, and lessening the danger of the wires being broken 100 in very cold weather.

The ends of the springs E E may be divided,

as shown in Fig. 5, so that the ends of the plates or wires may be placed in the slots and soldered therein or clinched, as shown in this figure, or they may be formed with the short slots, 5 *g g*, as shown in Fig. 6, so that the divided ends of the plates or wires may be passed through the slots and clinched, and in that manner secured to the springs.

Instead of forming the springs in the shape 10 of a half-circle or crescent form, as shown in the drawings, it is obvious that they might be of any other form and not depart from the spirit of my invention; but the half-circle or crescent form is preferred, as in that form they are 15 cheaply made and easily attached.

Having thus fully described my invention, I claim as new, and desire to secure by Letters Patent—

1. The hollow iron post *A*, formed with the 20 quadrangular T-slotted chamber *a*, in combination with the bolt *H* and nut *h*, washers *i i'*,

and the barbed plate *B*, whereby the barbed plate *B* or wire is secured to the post, substantially as shown and described.

2. The post *A*, cast with the T-slotted chambers upon one side, in combination with the washers *i* and *i'* and the bolt *H* and nut *h*, substantially as and for the purposes set forth. 25

3. The washer *i'*, formed with the flange *i''*, and the stop *j*, in combination with the bolt *H*, 30 nut *h*, washer *i*, and the T-slotted chamber of the post, substantially as and for the purposes set forth.

4. In a wire fence, the combination, with the barbed wires or plates *B*, having split or divided ends, of the spring-crest *E*, having its ends split or divided, as shown and described. 35

EDWARD RUANE.
